HAND TOOL

Fred J. Clemens, East Haven, Conn., assignor to
 K-D Manufacturing Company, Lancaster, Pa.,
 a corporation of Pennsylvania

Application October 5, 1932, Serial No. 636,361

10 Claims. (Cl. 81—5.1)

This invention relates to hand tools and more particularly to hand tools of the plier type having provision for releasably holding and retaining cone-shaped split keepers for the valve spring retainer disks of internal combustion engines, or the like, and for replacing or inserting them upon the valve stem. The operation of replacing or inserting such keepers in position on a valve stem has always been a tedious and difficult task, requiring considerable time and labor due to the engine structure at this point, especially as this operation has to be done while the retaining disk is held upwardly against the compression of the valve spring. The keepers not only have to be placed about the valve stem but also held there while the retaining disk is lowered into contact therewith. In many instances, the keepers slip from the position in which they are placed and drop into the crank case of the engine. These must be taken from the crank case or else others supplied in their place. The tool of this invention permits the user to dispose and hold the keepers in position about the valve stem with one hand while lowering the disk about the same with the other.

One of the objects of this invention is to provide an improved hand tool adapted for use in replacing or inserting cone-shaped split keepers, or the like, on a valve stem.

Another object is to provide such a hand tool with keeper engaging or holding means of such structure that the operation of replacing or inserting the same may be performed more quickly or readily than has been done in the past.

Still another object is to provide a hand tool for the above purpose which will be of comparatively simple structure, inexpensive to manufacture and particularly efficient in use.

A further object is to provide improved keeper engaging means in a tool of this type whereby the same will be adapted for use in replacing or inserting keepers of various sizes and shapes.

To these and other ends the invention consists in the novel features and combinations of parts to be hereinafter described and claimed.

In the accompanying drawing:

Fig. 1 is a top plan view of a hand tool embodying the features of this invention;

Fig. 2 is a side view of the same;

Fig. 3 is a section on line 3—3 of Fig. 1;

Fig. 4 is a section on line 4—4 of Fig. 1;

Fig. 5 is an enlarged top view of the jaws and associated parts of a hand tool of this invention, the jaws being shown in open position with keeper parts being held therein;

Fig. 6 is a side view of one of the jaws shown in Fig. 5;

Fig. 7 is an end view of the same;

Fig. 8 is a partial assembly of a valve stem, valve spring, retaining disk and keeper, and

Fig. 9 is a section on line 9—9 of Fig. 8.

The hand tool selected to illustrate the features of this invention is provided primarily for the purpose of replacing or inserting cone-shaped split keepers into their position about a valve stem of an internal combustion engine, but may be used for holding and retaining the parts of any generally cylindrically-shaped split bushing to replace or insert them where desired. This hand tool is preferably constructed of sheet metal whereby it is comparatively light in weight. It is of the plier type, comprising a pair of jaws 10 and 11, formed on the ends of extensions 12 and 13 of a pair of handles 14 and 15, respectively. The handles 14 and 15 are U-shaped in cross-section and are each provided with a pair of ears 16, the pair on one handle straddling the pair on the other and being pivoted together at this point by a pivot pin 17. A spring 18 is coiled about the pivot pin 17 and provided with extensions 19 and 20 that engage respectively the handles 14 and 15, to constantly urge them apart and in consequence urge the jaws 10 and 11 toward each other into closed position.

Each of the jaws 10 and 11 are formed integral with one of the handles by being disposed at the end of one of the extensions 12 and 13, which, in this instance, are continuations of one of the sides of the U-shape of each handle. The base of the U-shape of each handle is extended and forms an outer edge flange for the extensions 12 and 13, as shown at 21 and 22. The jaw portions 10 and 11 and the extensions 12 and 13 lie in the same plane with the inner edges thereof in opposed relation and with the flanges 21 and 22 disposed at substantially right angles thereto along the outer edges thereof. The extreme end of each jaw 10 and 11 is provided with an upwardly extending lug 23. A relatively short finger 24 extends rearwardly from the lug 23 substantially parallel to and along the inner edge of each jaw. The lug 23 extends from the inner edge of each jaw along the end edge and toward the outer edge thereof. The fingers 24 are of relatively thin material. In this instance, the lugs 23 and fingers 24 are formed from the sheet material forming the tool and are turned or bent into position therefrom, the fingers 24 being machine or otherwise worked to the required thinness.

A member 27 is slidably mounted upon each 55

extension 12 and 13, and each member is provided along one edge with a lug 25 corresponding to the previously described lug 23, and a finger 26 corresponding to the previously described finger 24. 5 The lug 25 is so disposed upon member 27 that it extends parallel to lug 23, and finger 26 is so disposed upon member 27 that it extends toward and in alignment with finger 24. The members 27 are formed by bending a strip of material downwardly 10 across the outside of each flange 21 and 22, as at 28, transversely across and underneath the respective extension 12 or 13, as at 29, upwardly over and about the inner edge of the extension as at 30, and transversely across the upper surface of the extension as at 31. The end of portion 31 of the member 27 abuts against the inside of each flange, as at 32, and by acting in cooperation with the portion 28 forms a comparatively long bearing on the respective flange whereby the member 27 is retained against rocking movement 15 whereby it might bind, and is guided in its sliding movements along the respective extension.

20 Each of the extensions 12 and 13 is cut away to receive portion 30 of member 27 and the recess 33 so formed is elongated axially of the tool and limits the sliding movement of the member 27 along the respective extension by forming shoulders 34 and 35 at each end of the recess 33. A coiled spring 36 is secured to the rear end of lug 30 23 and extends therefrom to the rear end of lug 25 to which it is also secured. The spring 36 is under tension at all times and constantly urges the member 27 toward shoulder 34 and therefore lug 25 and finger 26 toward lug 23 and finger 24. 35

30 The use for which the above tool is primarily intended is illustrated in the drawings, Figs. 8 and 9 illustrating one form of cone-shaped split keeper composed of two parts 40 and 41 assembled upon a valve stem 42 and retained thereon in a groove 43 by a spring retaining disk 44, which has a tapered recess formed therein that fits over the keeper parts. By this arrangement, the spring retaining disk 44 supports one end of a valve spring 45. The keepers are subject to 40 wear and occasional breakage and, therefore, 45 may require replacement. They may be removed by raising the disk 44 whereby the spring 45 is compressed and removing the keeper parts 40 and 41 from the valve stem 42 by hand. After 50 having removed the old ones, new keepers may be readily inserted by the use of the tool of this invention in the following manner. One part of the keeper is positioned in each jaw, as shown in Figs. 5, 6, and 7, wherein the keeper part 40 is shown pressed against the fingers 24 and 26 and clamped between the lugs 23 and 25 by the spring 36. The keeper parts 40 and 41 are disposed in this position by inserting the edge thereof behind finger 24 and against lug 23 and then 55 swinging it toward and into engagement with spring 36. Further movement in the same direction will cause the respective keeper part to engage the finger 26 and owing to the curvature of the keeper part will slide the member 27 along the adjacent extension and under, increasing tension 60 of spring 36 until the keeper part rides in back of finger 26. At this instant, the member 27 under the urge of spring 36 will be reversely moved, and lug 25 will engage the keeper part and 65 clamp it against lug 23 while the spring 36 will urge the part into close engagement with fingers 24 and 26. The keeper part is thus securely retained on the respective jaws. When the keeper is cone-shaped, as illustrated, the spring 36 not 70 only draws the lugs 23 and 25 together and the

keeper part toward the fingers 24 and 26, but also, due to its engagement upon the cone surface, urges the keeper part downwardly against the surface of the jaw. The spring 36, therefore, 5 may be said to perform a three-fold operation, that of clamping the keeper part against the lugs, of clamping it firmly against the fingers, and of seating it firmly upon the surface of the jaw.

After placing the keeper parts 40 and 41 in the tool jaws as above described, the tool is manipulated to position the keeper parts in place about the valve stem 42, as shown in Fig. 5. By releasing the handles 14 and 15, the jaws 10 and 11 are permitted to close and the keeper parts are then disposed upon the valve stem in the groove 43 15 thereon, the jaws 10 and 11 being each provided with a recess 46 in their opposing edges to provide clearance about the valve stem.

The disk 44 under pressure of spring 45 is then 20 permitted to lower whereby the undersurface of disk 44, as the latter embraces the keeper parts, gradually forces the tool downwardly and from engagement with the keeper parts. In some instances, the disk does not seat upon the keeper parts sufficiently to engage the tool and in such 25 cases the tool is lowered by the user until the spring 36, fingers 24 and 26 and lugs 23 and 25 ride off of the edge of the keeper part engaged thereby.

30 By the provision of the sliding member 27 carrying the lug 25, the finger 26 and the spring 36, keeper parts of various diameters, that is, smaller or larger than the one illustrated, may be inserted in the tool and placed in position on the 35 valve stem. Various forms of keeper parts other than cone-shaped ones may also be inserted in the tool and as efficiently retained therein, due to the holding effect obtained by the structure above described, especially in respect to the action 40 of spring 36. In view of this, the tool, due to its structure as described above, is substantially universal in its use.

45 By the structure and arrangement of the parts above described, a tool is formed that has been found to be particularly useful for the purpose of replacing or inserting keepers for valve retaining disks of combustion engines and which performs this operation in an efficient manner without the usual attendant disadvantages. The tool of this 50 invention is also of comparatively simple structure, positive in use and inexpensive to manufacture.

55 While I have shown and described a preferred embodiment of my invention, it will be understood that it is not to be limited to all of the details shown, but is capable of modification and variation within the spirit of the invention and the scope of the appended claims.

60 What I claim is:

65 1. In a hand tool, a pair of jaws movable toward and away from each other, each jaw having relatively movable and opposed members associated therewith, means on each jaw to position a valve spring retainer keeper or the like thereon, and means to continuously urge one of said members toward the other to clamp the keeper or the like therebetween, said means adapted to engage the keeper to urge it toward said positioning means.

70 2. In a hand tool, a pair of jaws movable toward and away from each other, each jaw having relatively movable and opposed members associated therewith, means on each jaw to position a valve spring retainer keeper or the like thereon, and means to move one of said members toward 75

the other to clamp the keeper or the like therebetween, said means adapted to engage the keeper to clamp it against said positioning means and upon the surface of said jaw.

5. 3. In a hand tool, a pair of jaws movable toward and away from each other, each jaw having relatively movable and opposed members associated therewith, means on each jaw to position a valve spring retainer keeper or the like thereon, and means to continuously urge one of said members toward the other to clamp the keeper or the like therebetween, said means adapted to engage the keeper to urge it toward said positioning means and toward the upper surface of said jaw.
10. 4. In a hand tool, a pair of jaws movable toward and away from each other, means on each jaw to releasably hold and retain a valve spring retainer keeper, said means comprising a lug and a finger extending upwardly from a face of said jaw and disposed at substantially right angles to each other and to the face of said jaw, a member mounted on said tool for movement toward and away from said lug, said member having a lug and a finger extending upwardly therefrom and disposed at substantially right angles to each other and to the face of said jaw, and means to urge said member towards said jaw to clamp the keeper between said lugs, said means being adapted to engage the keeper and urge it against said fingers.
15. 5. In a hand tool, a pair of jaws movable toward and away from each other, means on each jaw to releasably hold and retain a valve spring retainer keeper, said means comprising a lug and a finger extending upwardly from a face of said jaw and disposed at substantially right angles to each other and to the face of said jaw, a member mounted on each of said extensions for movement toward and away from the adjacent jaw, said member having a lug and a finger extending upwardly therefrom and disposed at substantially right angles to each other and to the face of said jaw, and means to urge said member toward said jaw to clamp the keeper between said lugs, said means being adapted to engage the keeper and urge it against said fingers and downwardly upon the face of said jaw.

20. 6. In a hand tool, a pair of jaws movable toward and away from each other, means on each jaw to releasably hold and retain a valve spring retainer keeper, said means comprising a lug and a finger extending upwardly from a face of said jaw and disposed at substantially right angles to each other and to the face of said jaw, a member mounted on said tool for movement toward and away from said lug, said member having a lug and a finger extending upwardly therefrom and disposed at substantially right angles to each other and to the face of said jaw, and means to urge said member towards said jaw to clamp the keeper between said lugs, said means being adapted to engage the keeper and urge it against said fingers and downwardly upon the face of said jaw.

25. 7. In a hand tool, a pair of jaws movable toward and away from each other, handle members to move said jaws, extensions between said handle members and said jaws, means on each jaw to releasably hold and retain a valve spring retainer keeper, said means comprising a lug and a finger, both extending upwardly from a face of said jaw and disposed at substantially right angles to each other and to the face of said jaw, a member mounted on each of said extensions for movement toward and away from the adjacent jaw, said member having a lug and a finger extending up-

wardly therefrom and disposed at substantially right angles to each other and to the face of said jaw, and means to urge said member toward said jaw to clamp the keeper between said lugs, said means being adapted to engage the keeper and urge it against said fingers.

5. 8. In a hand tool, a pair of jaws movable toward and away from each other, handle members to move said jaws, extensions between said handle members and said jaws, means on each jaw to releasably hold and retain a valve spring retainer keeper, said means comprising a lug and a finger, both extending upwardly from a face of said jaw and disposed at substantially right angles to each other and to the face of said jaw, a member mounted on each of said extensions for movement toward and away from the adjacent jaw, said member having a lug and a finger extending upwardly therefrom and disposed at substantially right angles to each other and to the face of said jaw, and means to urge said member toward said jaw to clamp the keeper between said lugs, said means being adapted to engage the keeper and urge it against said fingers and downwardly upon the face of said jaw.

10. 9. In a hand tool, a pair of jaws movable toward and away from each other, each jaw having relatively movable and opposed members associated therewith, means on each jaw to position a valve spring retainer keeper or the like thereon, and a spring member extending from one member to the other to urge one of said members toward the other to clamp the valve spring retainer keeper or the like therebetween, said spring member adapted to engage the keeper to clamp it against said positioning means.

15. 10. In a hand tool, a pair of jaws movable toward and away from each other, each jaw having relatively movable and opposed members associated therewith, means on each jaw to position a valve spring retainer keeper or the like thereon, and a spring member extending from one member to the other to urge one of said members toward the other to clamp the valve spring retainer keeper or the like therebetween, said spring member adapted to engage the keeper to clamp it against said positioning means and to urge it downwardly upon the surface of said jaw.

20. 11. In a hand tool, a pair of jaws, a releasable holder for a valve spring retainer keeper on each jaw, said holder comprising means to grip the keeper at oppositely disposed points, means to position the keeper on said jaw, and common means to operate said gripping means, and to engage the keeper to urge it into engagement with said positioning means and into engagement with the upper surface of said jaw.

FRED J. CLEMENS.
